OTTO STOLZ, OF BERLIN, GERMANY

DUMMY RIFLE

Application filed March 30, 1931, Serial No. 529,427, and in Germany October 10, 1930.

Firing practice weapons are known which mark the hits by projecting a light and shadow picture, the projection in one type of firing practice weapon being effected from within or beside the barrel, so that the direction of the rays follows the movement of the barrel; in another type the relatively movable intersection of the rays with the aiming device is rendered possible in that the barrel of a dummy rifle or pistol is movably mounted on the projection apparatus, so that the marked hit in the projection apparatus positively follows the straight line movements of the rear part of the aiming device.

The fundamental idea is with a dummy rifle or pistol to allow the hit to appear on a target surface for an unlimited length of time without subsequent physiological effects to the eye and also without the movable fitting hitherto necessary on a projection apparatus and is characterized in that in the barrel of the dummy through which a search-light shines two films or transparent discs are arranged, the target film being oscillatably suspended in a pendulum holding the balance, whereas upon the trigger being pulled, the hit film mounted on a hinge fixes the target disc in the position in which it is actually situated when the trigger is pulled. This arrangement of the dummy fire arm presents the advantage over the known firing practice weapons that both the target film and the hit film can be arranged the one on the other in the barrel, the hit position being dependent upon sure aiming and keeping steady as with a real firearm, because the bull's-eye of the target before the pulling of the trigger represents the bore axis and aiming direction of the barrel in the position showing the target.

An embodiment of the invention is illustrated in the accompanying drawing, in which:—

Fig. 1 shows the dummy rifle with illuminated aiming device in side elevation, partly in section.

Fig. 2 shows the target and hit films in elevation on a larger scale.

Fig. 3 is a top perspective view on a larger scale of the pendulum and the hit film in

conjunction with the double walled film frame partly in section.

The rifle consists of a barrel *a* and a butt *b*. In the rear portion of the barrel an electric bulb *e*, provided with a switch *c* and current lead *d*, is inserted. An asbestos layer *g* can be placed around a bulb cover *f* which is nickel-plated on the inner side. The asbestos layer serves for preventing the radiation of heat. In the middle portion of the barrel a double walled bored frame *h* is arranged, in which a transparent target film *i* is movably mounted, a lateral carrier *k* of the frame *h* carrying a ring-shaped pendulum *l*, the end *l'* of which carries the target film *i* by means of an eye *i'* also oscillatable in lateral direction and during the oscillation of the pendulum *l* raises and lowers the target film. In the front portion of the barrel a condensing lens *m* is mounted in a sleeve shiftable in the barrel *a*. A transparent hit film *n*, hinged on the lower end of the target frame *h* and having an opaque point in its centre, has a lever *o* extending through the wall of the barrel *a* into the lock box.

In the lock box a bar *p* is slidably mounted and a spring *p'* fixed at one end to the bar *p* and at the other end to the wall of the lock box tends to pull this bar towards the butt of the rifle. A spring *p''* is mounted at an incline on the bar *p* and under the lever *o* of the hit film *n*.

For bringing the rifle into fixing condition, the bar *p* is pulled towards the muzzle of the rifle by means of a knob projecting through a slot in the bottom of the lock box, thus tensioning the spring *p'*. The bar *p* is held in its forward position by means of a short hook of a spring-controlled trigger *s*, which engages in a hole in the bar *p*.

In order to take aim the rifle is held so that the target is projected on a wall or other flat surface. The rifle is then shifted until the sights are in alignment with the bull's eye of the projected target picture, whereupon the trigger is pulled.

During the aiming, the target film *i* oscillates in accordance with the movements of the rifle and when proper aim has been taken and the sights are in alignment with the bull's

eye of the projected target, the bull's eye of the target film is situated in the axis of the bore.

When pressure is exerted on the trigger, the hook is disengaged from the hole in the bar p so that the bar p is suddenly pulled towards the butt of the rifle by means of the spring r , causing the spring p^1 to bear against the lever o and swing the hit film n upwards against the target film, in which position it is held by the spring p^1 and fixes the target film in the position it actually occupies at the moment of impact.

The bulb then projects its rays through the two films so that the opaque point is projected with the target. As the point of the hit film always lies absolutely in the axis of the barrel bore when this film is in its swung up position, it will show on the projected picture the actual position of the axis of the bore at the instant when the trigger was pulled and thus indicate the accuracy of the aim.

The rifle can also be constructed so that it operates only after the insertion of a coin. For this purpose a slot V is provided behind the breach of the rifle and the butt b made hollow to form a coin collecting receptacle W . The end of the bar p projects towards the rear beyond this slot V and has an aperture for the passage of a coin and at its extremity a stop for holding the coin after insertion. On the under side of the butt opposite the slot V a rocker lever u is arranged which in normal position, that is before the insertion of a coin, assumes a position behind the trigger s and prevents same from oscillating, so that the rifle cannot be used.

If a coin t is inserted in the slot V it passes through the aperture in the end of the bar p and bears against the rear arm of the rocker lever u causing this lever to rock so that its other arm is lifted sufficiently to allow the trigger s to be actuated. In oscillating the trigger s bears against the front arm of the rocker lever u which presses against and slightly raises the rear end of the bar p so that the coin stop liberates the coin which runs into the collecting receptacle W .

I claim:—

1. A dummy rifle, comprising in combination with the barrel of the rifle, a source of light arranged in the rear end of said barrel, a double-walled frame having a central bore fixed in said barrel in front of said source of light, a carrier on said frame projecting towards the muzzle of said barrel, a ring-shaped pendulum on said carrier adapted to oscillate relative to said carrier and retain its vertical position as said barrel is inclined, an arm on said pendulum extending towards the rear of said barrel, a target film suspended on the rear end of said arm and vertically guided in said double frame but capable of lateral displacement when said barrel is turned to the right or to the left, a condenser

lens shiftable in the front end of said barrel adapted in conjunction with said source of light to project a picture of said target film on any flat surface used as aiming screen, said target film adapted through the intermediary of said arm and said pendulum to oscillate in any direction relative to said barrel so that when said barrel is in horizontal position, the centre of said target film coincides with the centre of said barrel.

2. A dummy rifle as specified in claim 1, comprising in combination with the rifle barrel, the target film, the double walled frame, the source of light and the lock box of the rifle, a transparent hit film having an opaque point in its centre hingedly mounted on the lower end of the rear wall of said frame, a lever extending from said hit film through the wall of said barrel into said lock box, a shiftable bar in said lock box, a pull spring in said lock box connected to said lock box and to said shiftable bar adapted to suddenly pull said bar towards the rear, and an inclined spring on said bar adapted to bear against said lever to oscillate and bring said transparent hit film against said ring target with its opaque point in the centre of the barrel bore and to hold said target film in the position it actually occupies at the instant of impact so that said source of light projects the picture of said target film with the centre point of said transparent hit film indicating the position of the target relative to the centre of the barrel.

In testimony whereof I affix my signature.

OTTO STOLZ.
